UNITED STATES PATENT OFFICE

154,403

DESIGN FOR A HORIZONTAL SINGLE-CYLINDER HOPPER-TYPE DIESEL ENGINE

Frank J. Kogel, Burbank, Calif.

Application September 2, 1947, Serial No. 141,156

Term of patent 14 years

(Cl. D77—1)

To all whom it may concern:

Be it known that I, Frank J. Kogel, a citizen of the United States, residing at Burbank, in the county of Los Angeles and in the State of California, have invented a new, original, and ornamental Design for a Horizontal Single-Cylinder Hopper-Type Diesel Engine, of which the following is a specification, reference being had to the accompanying drawings, forming part thereof:

Figure 1 is an elevational view taken from one side of a horizontal single-cylinder hopper-type Diesel engine embodying my new design;

Figure 2 is an elevational view taken from the opposite side thereof;

Figure 3 is a perspective view of the top, one side and one end of said engine; and

Figure 4 is a perspective view of the top, the opposite side and the opposite end thereof.

I claim:

The ornamental design for a horizontal single-cylinder hopper-type Diesel engine, as shown.

FRANK J. KOGEL.
